(57) **CLAIM**

The ornamental design for a toy, as shown and described.

DESCRIPTION

FIG. 1 is a perspective view of a toy showing my new design.

FIG. 2 is another perspective view of a toy.

FIG. 3 is a front view of a toy.

FIG. 4 is a rear view of a toy.

FIG. 5 is a left side view of a toy.

FIG. 6 is a right side view of a toy.

FIG. 7 is a top view of a toy; and,

FIG. 8 is a bottom view of a toy.

The broken lines illustrate portions of the toy that form no part of the claimed design.

1 Claim, 8 Drawing Sheets
